UNITED STATES PATENT OFFICE.

ALDER F. CONNERY, OF SPRINGFIELD, NEW YORK, ASSIGNOR OF ONE-HALF TO POSTAL TELEGRAPH-CABLE COMPANY, OF NEW YORK, N. Y., A CORPORATION OF NEW YORK.

REGENERATIVE VIBRATORY REPEATER FOR TELEGRAPH CIRCUITS.

Application filed October 6, 1923. Serial No. 687,655.

To all whom it may concern:

Be it known that I, ALDER F. CONNERY, a subject of the King of Great Britain, and resident of Springfield, Long Island, in the county of Queens and State of New York, have invented certain new and useful Improvements in Regenerative Vibratory Repeaters for Telegraph Circuits, of which the following is a specification.

10 Repeaters of the ordinary type, such as an ordinary relay, are used on telegraph lines or circuits where the distance between the terminal stations is too great to be worked direct. Long lines are frequently 15 divided into a number of sections with repeater stations between the sections, so that a number of repeaters will be used on the same line or circuit. The ordinary type of repeater merely strengthens the current for 20 the next line section and does not correct any distortion in the received signals. Such a repeater will sometimes add further distortion to an already distorted signal, dependent upon adjustments and varying atmospheric conditions. Where a circuit is 25 very long and contains many repeaters of the ordinary type, and the lines are subject to varying weather conditions and other causes which tend to mutilate and distort the 30 signals, it is only possible to work the circuit at a very slow speed as compared with the speed of the shorter circuits.

Where machine telegraphy is used, and the transmitted signals are of unit or multiple unit length, the units being time intervals, repeaters of the regenerative type are used, which not only strengthen the signals for the next line section but also correct 35 any slight distortion in the received signals so that the repeated signals will be in precisely the same form as first transmitted 40 from the terminal station. These regenerative repeaters embody a rotating apparatus which must be timed to rotate in synchronism with the rotating transmitting apparatus. This type of repeater is complicated; 45 difficult to adjust and to maintain in synchronism with the transmitting apparatus.

50 A well known example of a rotary repeater of the regenerative type is the Baudot repeater. This repeater has a rotor which revolves in synchronism with the distributor at the terminal set. Means are provided for keeping the rotor revolving in synchronism

with the distributor, which means utilizes 55 special correcting signals transmitted from the terminal distributor at each revolution thereof.

The main object of this invention is to provide a regenerative vibratory repeater 60 and to provide means whereby said repeater will vibrate in synchronism with the signals as sent out by the transmitting apparatus.

Another important object of the invention 65 is to provide means whereby the received signals will operate the means for maintaining the repeater in synchronism with the signals transmitted from the terminal set. It is manifest that by the use of a vibratory 70 repeater maintained in synchronism by the received signals I avoid the use of all rotating parts and the use of special correcting signals sent out from the terminal set.

Another object of the invention is to utilize 75 a vibrating element in the form of a reed or fork to make the necessary electrical contacts, instead of the usual rotary distributor; and to provide means whereby the incoming signals will maintain said vibrating element in synchronism with the received 80 signals.

A repeater constructed in accordance with this invention is, therefore, simple and of 85 moderate cost and easily maintained in correct operating condition.

In the drawings, Figure 1 is a diagrammatic view of a simple one-way circuit showing a transmitter or terminal apparatus and 90 one regenerative repeater set;

Fig. 2 shows graphically the regenerative 95 action of the repeater; and

Fig. 3 illustrates graphically the synchronous movement of the vibrating element and the signal units.

Referring to Fig. 1, 1 designates a transmitting terminal set. This transmitting apparatus may be of any suitable form, that shown indicating a transmitting set in which the five-unit code is used; 2 designates the five transmitting keys which are operated in the usual manner to transmit signals to the line, said signals being of unit length or of multiple-unit length. These signals are transmitted to the line through the distributor 3. As is well known, the signals sent out on the line are made up of what are known as spacing and marking impulses,

sai spacing and marking impulses flowing from current sources of different sine.

In Fig. 1, MLR designates a main line relay which receives the incoming signals from the line. TR designates a transmitting relay through which the regenerated signals are sent out on the next line section. LR designates a relay interposed between the main line relay and the transmitting relay and might properly be called a locking relay, its function being to ensure firm signals through the transmitting relay and to protect the transmitting relay from the influence of the tongue of the main line relay while the local operating current is flowing through the windings of the transmitting relay. SR designates a switch relay; CR a corrector relay.

All of these relays are polarized and have differential windings, the curved lines A to B representing one winding and the curved lines C to D representing the other winding. Each relay is provided with a tongue T and with a spacing contact S and a marking contact M. A current flowing from A to B or from C to D will cause the tongue T to make contact with stop S, while a current flowing from B to A or from D to C will cause the tongue T to make contact with the stop M. The polarized relays may be centered so that with no current flowing through the windings the tongue will cling to either contact when so placed.

While in Fig. 1 the windings of the main line relay MLR are shown as joined in series and connected between the line IN and ground for the purpose of making the illustration simpler, in actual practice, when used in differential duplex circuits, one winding of MLR will be in the real line circuit and the other winding in the artificial line circuit.

TF designates a vibrating element in the form of a tuning fork. This fork is electrically driven by means of a driving magnet DM and driving contact DC. It is caused to vibrate in the manner of a common bell or buzzer. This form of device is well known and need not be more particularly described herein. A resistance SR and a condenser CO in series suppress the sparking at the driving contact DC. Large changes in the period of vibration of the vibrating element may be made by adjusting the movable weights MW to different positions on the tines of the tuning fork. AM designates an adjusting magnet and AR an adjusting rheostat. Small changes in the period of vibration of the tuning fork may be made by increasing or decreasing the current in the adjusting magnet AM by means of the rheostat AR. The adjusting magnet exerts a magnetic braking effect upon the tines of the tuning fork and causes the

amplitude of the vibrations to be reduced. This reduction of amplitude increase the speed or period of vibration. Therefore, increasing the current in the adjusting magnet AM by means of the rheostat causes the speed of vibration of the tuning fork to be increased. CM designates a corrector magnet which also acts magnetically upon the tuning fork in the same manner as the adjusting magnet AM, and a current through the corrector magnet will cause the speed of vibration of the tuning fork to be increased. The current through the adjusting magnet is constant. The flow of current through the corrector magnet is controlled by the corrector relay. The adjusting magnet, therefore, exerts a constant influence upon the tuning fork while the corrector magnet is intermittent in its operation, being controlled through the operation of the corrector relay as will be fully hereinafter described.

The tuning fork is provided with a tongue LT which is arranged to vibrate between and to engage a left corrector contact LCC and a right corrector contact RCC. The tuning fork is also provided with a tongue RT which is arranged to vibrate between and to engage the driving contact DC and a selecting contact SC.

The line IN is connected to the transmitter of the terminal set which transmits positive and negative currents of unit or multiple-unit duration, and these currents or signals from the line pass through the windings of relay MLR to ground and cause the tongue T of the said relay to rest on either contact S or M, dependent upon the direction of the current. The contacts S and M of the main line relay are connected to current sources of different sine.

RR designates a reading relay. The windings of this relay are connected between the tongue T of the main line relay and ground. Any movement of the tongue of the main line relay will be followed by a movement of the tongue of the relay RR. RS designates a reading sounder, which is in circuit with the tongue and marking contact of the reading relay. When the tongue T and stop M of relay RR make contact the reading sounder will be operated. The reading relay and the reading sounder are not essential to this apparatus but may be conveniently used. The repeater attendant may conveniently receive instructions by means of the sounder RS. When the circuit is being worked through from terminal station to terminal station by the regular automatic means the sounder RS may be silenced by shunting the circuit around its coils by means of switch SS.

The tongue T of the main line relay is connected to the winding B to A of the relay LR when the levers of switch ACS are

thrown to the right. Therefore any movement of the tongue of the relay MLR will be followed by a movement of the tongue of the relay LR assuming no current to be flowing in the D to C winding of relay LR. The contacts S and M of the relay LR are connected to current sources of different sine. The tongue T of the relay LR is connected through the D to C winding of relay LR and thence to the windings of the transmitter relay TR, as will be more fully hereinafter described.

It is necessary that the tuning fork TF vibrate in synchronism with the received line signal. For each unit length of signal received over the line IN the tuning fork must make one complete cycle of vibration. If the received line signals are alternately positive and negative in sine and each signal is of unit length, this combination of signals is known as an alternating current or "AC" and will cause tongue T of the relay MLR to vibrate in synchronism with the line signals. In this case the tuning fork will be vibrating at double the frequency of the tongue T of the relay MLR.

The means for maintaining the tuning fork vibrating in synchronism with the line signals is as follows:

30 The tuning fork must be first adjusted by means of the movable weights MW and the adjusting rheostat AR until it will make slightly less than a complete cycle of vibration for each unit length of received line signal when there is no current through the corrector magnet. The corrector magnet when energized must exert a magnetic effect on the tuning fork sufficient to cause the period of vibration, that is to say the speed of vibration, to be increased so that the tuning fork will make slightly more than a complete cycle of vibration for each unit length of received line signal. The result of this arrangement is that when the corrector magnet CM is not energized the tuning fork will vibrate at too low a frequency and when corrector magnet is energized the tuning fork will vibrate at too high a frequency.

50 An automatically operating correction means causes corrector magnet CM to become de-energized when the frequency of the tuning fork gets ahead of the frequency of the line signal units, and also causes the corrector magnet to become energized when the frequency of the tuning fork falls behind the frequency of the line signal units. This automatic correction is accomplished by means controlled and operated by the signal impulses received by the main line relay, as hereinafter described.

The tongue of the main line relay is connected to both windings of relay SR in series and thence to ground through contact LCC and the tuning fork. Therefore, the

relay SR will be under the influence of the tongue of the main line relay only when the tuning fork tongue LT is making contact with LCC. Another circuit from the tongue

T of the relay MLR goes through fixed condenser FC to tongue T of relay SR. The stop S of relay SR is connected to the winding A to B of relay CR, and the stop M

of relay SR is connected to winding D to C of the corrector relay CR, so that the circuit from tongue T of relay SR must be through one of the windings of relay CR

70 and thence to ground through contact RCC and the tuning fork. Any current impulse from condenser FC must pass through either

one or the other winding of relay CR and the position of the tongue of relay SR determines which winding of relay CR the condenser impulse will go through. When

75 the tuning fork is making connection with contact RCC a positive impulse on terminal A or a negative impulse on terminal D of relay CR will throw the tongue of that relay to the left, but a negative impulse on terminal A or a positive impulse on terminal

20 D of relay CR will throw the tongue of that relay to the right. If the tongue of relay

MLR should move from right to left or from left to right at the moment that the tongue LT of tuning fork TF is making

25 contact with contact RCC the impulse from condenser FC will throw the tongue of relay CR to the left. Assuming the tongue

LT of the tuning fork on contact RCC when the tongue of MLR moves from right to

30 left, that is from M to S, the tongue of relay SR, will remain on its stop M and the impulse from the condenser FC will flow

35 through winding C to D and tongue of relay CR will move to the left to stop S.

When, however, the tongue of relay MLR moves from left to right, from stop S to

40 stop M, the tongue of relay SR will remain on its stop S, and the impulse from the con-

45 denser will flow through winding A to B of relay CR and the tongue of said relay CR

45 will be moved to the left to stop S. When the tongue of relay MLR moves from right

50 to left or from left to right at the moment that the tongue LT of tuning fork TF is

55 making contact with contact LCC, then tongue T of relay CR will be thrown to the

60 right due to the condenser impulse from condenser FC just as soon as tongue LT makes

65 contact with RCC. The impulse from the condenser can only take place when tongue

70 LT engages contact RCC, and the tongue of relay SR moves only when tongue LT en-

75 gages contact LCC.

75 It should be noted that each time tongue

80 T of relay MLR moves from one contact to the other a short impulse from condenser

85 FC will pass through one of the windings of relay CR. If this movement of the

90 tongue of relay MLR should occur when

the tuning fork is touching contact RCC then the condenser discharge will immediately occur, and as tongue T of relay SR will not move because the tuning fork is not touching contact LCC the tongue of relay CR will be thrown to stop S by the condenser discharge.

If, however, this movement of tongue T of relay MLR should occur when the tuning fork is touching contact LCC the discharge from condenser FC through relay CR will be delayed until the tuning fork touches contact RCC, but this movement of tongue T of relay MLR occurring when the tuning fork is making contact with LCC will cause movement of tongue T of relay SR and the condenser discharge which occurs when the tuning fork touches contact RCC will throw the tongue T of relay CR to the stop M.

It will be evident that for each movement of the tongue of the main line relay there will be a discharge from condenser FC and if this movement of the main line relay occurs when the tuning fork is touching contact LCC the tongue of the switch relay SR will move so the condenser discharge throws the tongue of corrector relay CR to the right, but if this movement of the tongue of the main line relay should occur when the tuning fork is touching RCC the switch relay will not be moved and the condenser discharge will throw the tongue of the corrector relay CR to the left.

The relay SR acts as a switch relay and switches the condenser discharge through either one or the other of the windings of the relay CR so that the tongue of the relay CR will be moved either to right or left. If the tongue of the main line relay moves when the tuning fork is touching one of its contacts the relay SR will move and switch the condenser impulse through relay CR so its tongue will move in a certain direction. If the tongue of the main line relay moves when the tuning fork is touching the other contact the relay SR will fail to move and the condenser impulse will move the tongue of relay CR in the other direction.

The stop M of the corrector relay CR is connected to a source of positive current and to the forward stop F of a holding relay HR. The armature of this holding relay is connected to the tongue of the relay CR and to one side of the winding of the holding relay magnet HM. The other side of this winding is connected to the stop S of the corrector relay and also to the winding of the corrector magnet CM. In this connection is arranged a switch CS by means of which the corrector magnet may be entirely disconnected from the corrector relay and the holding relay. The armature of the holding relay is normally held against its back stop by a spring. The tongue T and the stops S and M of the corrector relay CR

are connected to the holding relay HR in such manner that when the tongue T of the corrector relay is on stop M the armature *a* of the holding relay will be held against the forward contact stop F and the resultant current through magnet HM will hold the armature *a* against said stop and a steady current will be maintained in the corrector magnet CM of the tuning fork even though the tongue T of the relay CR tends to chatter on its contact M. When the tongue T of the relay CR makes contact with the stop S the windings of the magnet of the holding relay HR will be shunted and the armature *a* will fall back and break the current flow through the corrector magnet of the tuning fork. It will be seen, therefore, that when tongue T of the corrector relay makes contact with its stop M current flows through the corrector magnet, and that when the tongue makes contact with stop S current ceases to flow through the magnet CM. It also will be seen that the holding relay HR is connected in the corrector magnet circuit in such manner that any tendency of tongue T of the relay CR to chatter on its contact stops is not reflected in a fluctuating current in the corrector magnet of the tuning fork.

The tongue of the relay LR is connected through its own winding D to C to the terminal B of the winding B to A of the transmitting relay TR, the terminal A of said winding being connected to the selecting contact SC of the tuning fork. The tongue T of the transmitting relay is connected to the "out" section of the line and is also connected to the terminal C of the winding C to D of the said relay. The terminal D of said winding is connected to ground through a leak resistance *lr* when the levers of switch ACS are in the normal or right hand position. The stop S of the transmitting relay is connected to a source of positive current and the stop M thereof is connected to a source of negative current. The stops S and M are connected through a pole-changing key K to the OUT line through a switch KS. This key may be thrown into the OUT line circuit for the purpose of transmitting signals by hand.

The operation of the apparatus is as follows:

The period of vibration of the tuning fork is set by means of the movable weights MW and the adjusting rheostat AR so that it makes slightly less than a complete cycle of vibration for each unit length of received signal when no current flows through the corrector magnet CM, and makes slightly more than a complete cycle of vibration for each unit length of received signal when current flows through the corrector magnet CM. As hereinbefore pointed out the movement of the tongue of the main line relay MLR will be controlled by the distant trans-

mitter which sends out positive and negative currents of unit or multiple-unit duration, and the said tongue T will move at unit or multiple-unit intervals, assuming no distortion of the received line signals. If the vibration of the tuning fork is in such phase relation with the movements of the tongue of the main line relay that the tongue LT of the tuning fork is making contact 5 with the stop RCC at the instant that the tongue of the relay MLR moves to contact S or to contact M then the tongue of the relay CR will be moved to its stop S and the corrector magnet CM will be de- 10 energized and the period of the tuning fork will be reduced. The phase relation between the tongue of the relay MLR and the tuning fork will now change and within a short period of time the tongue LT of the tuning fork will make contact with LCC at the instant that the tongue of the relay MLR makes contact with its stop either S or M. The tongue of the corrector relay CR will now be moved to its stop M 15 and the corrector magnet will be energized, whereby the period of vibration of the tuning fork will be increased. The tuning fork will be thus maintained in synchronism and in approximate phase relation with received signals. In actual operation tongue T of relay MLR will be in transit between its contacts S and M when the tongue LT of tuning fork TF is about to leave stop LCC, is in transit between stops LCC and 20 RCC, or is just making contact with stop RCC. If the received signals are mutilated so that they are shortened or lengthened as compared with the signals sent out by the transmitting station, and, therefore, the tongue of relay MLR does not move at exactly unit or multiple unit intervals, there will be a speeding up and slowing down of the period of vibration of the tuning fork, but since the speeding up and slowing down 25 effect on the tuning fork due to corrector magnet CM is quite small and must persist for a considerable time before the vibration of the tuning fork can get far out of relative phase relation with the received signals, this system of holding the tuning fork in step with the line signals is very effective even though the received line signals are considerably distorted.

When the correcting system is holding 30 the tuning fork in step with the received unit signal lengths it will be noted that tongue RT of tuning fork will make contact with stop SC once for each unit length of contact of tongue T of relay MLR on stop either S or M, and it also will be noted that current will flow through winding B to A of transmitting relay TR each time tongue RT of the tuning fork makes contact with the stop SC, and that the direction of said 35 current will be governed by which stop the

tongue of relay LR is making contact with. The movements of tongue T of relay LR are governed by the received line signals through relay MLR while there is no current flowing through winding D to C of relay LR. Since a current of proper direction through winding B to A of transmitting relay TR will move its tongue T from one contact stop to the other, it will be seen that the instant when the tongue of the transmitting relay moves, if it moves, is governed by the contact of tongue RT of tuning fork with stop SC; but whether or not it moves and the direction of its movement depend upon which contact stop 40 tongue T of relay LR is making contact with. It should be noted that when tongue RT of the tuning fork is making contact with stop SC the current which flows through winding B to A of relay TR also passes through winding D to C of relay LR and the direction of this current through relay LR will be such as to hold its tongue firmly to the contact which it may be touching. This current through winding 45 D to C of relay LR will be of greater strength than the current in winding B to A and therefore the relay LR will not be under the influence of the main line relay MLR while transmitting relay TR is connected to relay LR by means of tongue RT of the tuning fork making contact with stop SC. This locking current in the D to C winding of the relay LR is important in 50 that it insures the tongue of relay LR from movement while the transmitting relay TR is connected to relay LR and therefore the repeated signals from relay TR will be of full length. Were this locking arrangement on relay LR not provided a movement of the tongue of the main line relay occurring while the tongue RT of the tuning fork was touching stop SC would cause a corresponding movement of the tongues of relays LR and TR and in order to minimize this detrimental effect the stop SC of the tuning fork would have to be adjusted in such a manner as to cause it to make very short contact duration with the tongue RT. The locking current, however, through the D to C winding of the relay LR, makes unnecessary any special adjustment of the stop SC of the tuning fork and the stop SC may make a long contact duration with tongue RT of the tuning fork, and the locking circuit through the D to C winding of the relay LR will insure that the repeated signals will be of unit or multiple-unit length.

The S and M contact stops of transmitting relay TR are connected to the main line current sources of different sine. The connection to the outgoing line is taken from tongue T of relay TR. While as shown the line marked OUT leads direct to the line for single-line work, it will be understood that

when this repeater is used on duplex lines the line marked OUT will lead to the apex of the real and artificial lines of the opposite half of the complete repeater set.

5 During the time that tongue RT of the tuning fork is not making contact with stop SC there will be no current flowing through the B to A winding of transmitting relay TR, and any slight jar or vibration of the 10 transmitting relay TR might cause its tongue T to leave the stop it is making contact with. In order to ensure firm and reliable contacts a leak is taken off tongue T and through the C to D winding and through a high resistance b_r to ground, when switch ACS is in its 15 normal or right hand position. The current through the C to D winding is always in such direction as to hold the tongue to which ever stop it may be in contact with. The 20 value of the current in the C to D winding is, however, much less than the full value of the current in the B to A winding and this leak holding current through winding C to D does not interfere with the proper 25 movement of tongue T, by means of current in the B to A winding.

Fig. 2 shows graphically the regenerative action of the repeater. The line I shows the signals of unit and multiple-unit length 30 either positive or negative as transmitted by the sending station. The line II shows the manner in which the distorted signals as received at the repeater set may operate relay MLR shown in Fig. 1. It will be 35 seen that in this illustration the S or spacing signals have been clipped or shortened, while the M or marking signals have been lengthened. Line III shows the movement of the tongue of locking relay LR. The heavy 40 dashes on line IV denote the contact moments of the contact tongue RT and stop SC of tuning fork TF shown in Fig. 1, during which contact moments transmitting relay TR may be operated by relay LR. 45 Line V shows the regenerated signals as transmitted by the tongue T of transmitting relay TR shown in Fig. 1. The regenerated signals are all of unit or multiple-unit length and are exact duplicates of the 50 signals shown on line I.

It is to be understood that the apparatus herein described will correct any distortion in signals that is less than one-half a complete unit. If the distortion of the signal 55 is greater than one-half a unit period so that the signal impulse will be maintained beyond the moment of contact of the tongue RT with the selecting contact SC which, in the normal operation of the signal, should 60 show a reversal of current in the main line relay and in the LR relay, then the distortion in the signal will persist for the full unit period until the next contact of the tongue RT with the selecting contact SC.

65 The moment of contact of the tongue RT

with the selecting contact SC marks the signal unit periods so that the signal impulses sent out through the transmitting relay will be defined by the vibration of the tongue RT and its contact with the stop SC.

No adjustable means is provided to insure that the contact RT of the tuning fork will make contact with stop SC at the proper moment with respect to the received signals for experience has proven that this adjustable means is unnecessary on a repeater of this type. On a regenerative repeater of the rotary type this adjustable means is considered necessary and the adjustment of this means is termed "orientation."

The correction in the distortion of the signals is accomplished by the tuning fork through its cooperation with the LR relay and the transmitting relay. To bring about this correction of the distortion in the signals it is only necessary that the tuning fork shall vibrate in synchronism with the incoming signals of unit length.

It has been found useful on regenerative telegraph repeaters to be able to generate 90 locally and to transmit signals of unit length and of constantly changing polarity to the outgoing line for use in balancing purposes. Referring to Fig. 1 ACS is a double throw double pole switch whose normal position is to the right. When both levers of this switch are thrown to the left the leak current from tongue T of relay TR through winding C to D and through leak resistance b_r instead of going direct to ground will first pass 95 through windings B to A of relay LR. Assuming no current in the C to D winding of relay LR this leak current through winding B to A of relay LR will cause the tongue to move to a different position than that occupied by the tongue of relay TR. When tongue RT of the tuning fork makes contact with stop SC then the tongue of relay TR will move to correspond with the position 100 of the tongue of relay LR. This movement of the tongue of relay TR will, of course, change the direction of the leak current through winding B to A of relay LR but as long as tongue RT of tuning fork makes contact with stop SC the locking current 105 through the D to C winding of relay LR will prevent this leak current operating it. As soon as the tongue RT of the tuning fork breaks contact with stop SC the locking current in the D to C winding of relay LR will cease and the tongue of relay LR will now move under the influence of the 110 leak current in the A to B windings. It will be seen that when the tuning fork tongue RT makes contact with SC the tongue of relay TR will be moved to correspond with the tongue of relay LR and that when the tuning fork tongue RT breaks contact with SC the tongue of relay LR will 115 be moved to a position not corresponding 120

125

130

135

- with the tongue of relay TR. As long as the tuning fork TF vibrates the tongues of relays LR and TR will also vibrate though the frequency of vibration of the relays will be one-half of that of the tuning fork.
5. When this repeater is used on duplex telegraph lines and it is desired to regenerate the signals passing in both directions, twice the amount of apparatus shown in Fig. 1 will, of course, be required, as well as duplex balancing equipment.
10. While the largest application of this repeater will probably be on telegraph lines worked by means of some automatic system such as a multiplex printing telegraph system, its use is by no means limited to physical telegraph lines and it may be used to repeat signals received over carrier current systems, submarine cables, radio telegraph systems and other signalling means.
15. What I claim is:
1. A regenerative vibratory repeater apparatus for telegraph circuits, comprising a signal receiving apparatus, a vibrating element, a signal transmitting apparatus, means whereby the time of operation of the transmitting apparatus will be controlled by the vibrating element, and means electrically connecting the transmitting apparatus to the signal receiving apparatus independently of the said vibrating element whereby the character of the signals sent out by the transmitting apparatus will be governed by the signal impulses received by the receiving apparatus.
20. 2. A telegraph system comprising a means for transmitting signals of units or multiple unit length of opposite polarities, a signal receiving apparatus, a signal transmitting apparatus, a vibrating element, means whereby the signal receiving apparatus and the vibrating element will cause the transmitting apparatus to transmit signals of unit or multiple unit length and of opposite polarities, and means operating independently of the said vibrating element whereby the signal receiving apparatus will control the character or polarities of the signals transmitted by the transmitting apparatus, the unit length of the signals transmitted by the transmitting apparatus being controlled by the signal receiving apparatus and the vibrating element.
25. 3. A regenerative vibratory repeater apparatus for telegraph circuits comprising a main line relay, a vibrating element, a transmitting relay, means whereby the time of operation of the transmitting relay will be controlled by the vibrating element, and means electrically connecting the transmitting relay to the main line relay independently of the said element whereby the character of the signals sent out by the transmitting relay will be governed by the signal impulses received by the main line relay.
4. A regenerative vibratory repeater apparatus for telegraph systems wherein the signals transmitted are of unit length or multiple unit length, comprising a main line relay, a vibrating element, a transmitting relay, means whereby the vibrating element will permit the transmitting relay to operate only at signal unit intervals, and means connecting the transmitting relay to the main line relay independently of the said vibrating element whereby the character of the signals sent out by the transmitting relay will be governed by the signal impulses received by the main line relay.
5. A regenerative vibratory repeater apparatus for telegraph systems wherein the signals transmitted are of unit length or multiple unit length, comprising a main line relay, a vibrating element, a transmitting relay, means whereby the vibrating element will permit the transmitting relay to operate only at signal unit intervals, means connecting the transmitting relay to the main line relay independently of the said vibrating element whereby the character of the signals sent out by the transmitting relay will be governed by the signal impulses received by the main line relay.
6. A regenerative vibratory repeater apparatus for telegraph systems wherein the signals transmitted are of unit length or multiple unit length, comprising a main line relay, a vibrating element, a transmitting relay, means whereby the vibrating element will permit the transmitting relay to operate only at signal unit intervals, means connecting the transmitting relay to the main line relay whereby the character of the signals sent out by the transmitting relay will be governed by the signal impulses received by the main line relay, and means interposed between the main line relay and the vibrating element and operated by the received signals to increase or decrease the speed of the vibrating element thereby to maintain the vibrating element in synchronism with the units of the received signals.
100. 6. A regenerative vibratory repeater apparatus for telegraph systems wherein the signals transmitted are of unit length or multiple unit length, comprising a main line relay, a vibrating element, a transmitting relay, means whereby the vibrating element will permit the transmitting relay to operate only at signal unit intervals, means connecting the transmitting relay to the main line relay whereby the character of the signals sent out by the transmitting relay will be governed by the signal impulses received by the main line relay, a switch relay operated by the main line relay, a corrector relay controlled by the switch relay and the vibrating element, and means operated by the corrector relay to maintain the vibrating element in synchronism with the units of the signals received by the main line relay.
105. 7. A regenerative vibratory repeater apparatus for telegraph systems wherein the signals transmitted are of unit length or multiple unit length, comprising a main line relay, a vibrating element, a transmitting relay, means whereby the vibrating element will permit the transmitting relay to operate only at signal unit intervals, means connecting the transmitting relay to the main line relay whereby the character of the signals sent out by the transmitting relay will be governed by the signal impulses received by the main line relay.

by the main line relay, a switch relay operated by the main line relay, a corrector relay controlled by the switch relay, means operated by the corrector relay to maintain the 5 vibrating element in synchronism with the units of the signals received by the main line relay, and means whereby the operation of the corrector relay to increase or decrease the speed of the vibrating element 10 will be controlled by the vibrating element.

8. A regenerative vibratory repeater apparatus for telegraph systems wherein the signals transmitted are of unit length or multiple unit length, comprising a main line 15 relay, a vibrating element, a transmitting relay, means operated by the vibrating element to permit current to flow through the transmitting relay at signal unit intervals, means connecting the transmitting relay to 20 the main line relay independently of the said vibrating element whereby the character of the signals sent out by the transmitting relay will be governed by the signal impulses received by the main line relay, and corrector 25 means operated by the received signals and the vibrating element to maintain the vibrating element in synchronism with the units of the received signals.

9. A regenerative vibratory repeater apparatus for telegraph systems wherein the signals transmitted are of unit length or multiple unit length, comprising a main line 30 relay, a vibrating element means for normally maintaining the said element vibrating 35 at a slower speed than the received signal units, a corrector magnet for causing the vibrating element to vibrate at a slightly higher speed than the received signal units, a switch relay connected to the main line 40 relay and operated thereby, a corrector relay connected to the switch relay and controlled thereby, means operated by the corrector relay to render the corrector magnet operative or in-operative, means 45 operated by the vibrating element to control the operation of the corrector relay, a transmitting relay, means whereby the vibrating element will permit the transmitting relay to operate only at signal unit intervals, and means connecting the transmitting relay to 50 the main line relay whereby the character of the signals sent out by the transmitting relay will be governed by the signal impulses received by the main line relay.

55 10. A telegraph system comprising a means for transmitting signals of unit or multiple unit length and of opposite polarities, a main line relay, a transmitting 60 relay, a vibrating element, a corrector means interposed between the main line relay and the vibrating element and controlled by the vibrating element to maintain said vibrating element in synchronism with the units of the received signals, means whereby the main 65 line relay and the vibrating element will

cause the transmitting relay to transmit signals of unit or multiple unit length, and means independent of the said vibrating element whereby the main line relay will control the character of the signals transmitted by 70 the transmitting relay, the unit length of the signals transmitted by the transmitting relay being controlled by the main line relay and the vibrating element.

11. A regenerative vibratory repeater apparatus for telegraph systems wherein the signals transmitted are of unit length or multiple unit length, comprising a main line relay, a vibrating tuning fork having two arms one arm carrying a tongue LT and the other arm carrying tongue RT, a pair of contacts LCC and RCC for said tongue LT, a pair of contacts DC and SC for the said tongue RT, a transmitting relay having one of its coils electrically connected to the SC 85 contact of the tuning fork, the other coil of said transmitting relay being connected to the relay tongue and to ground through a leak resistance, a locking relay having one of its coils connected to the relay tongue and to 90 that coil of the transmitting relay which is electrically connected to the SC contact of the tuning fork, the other coil of the said locking relay being connected to ground and to the tongue of the main line relay, 95 a switch relay having its coils connected in series with one terminal connected to the tongue of the main line relay and the other terminal connected to the LCC contact of the tuning fork, an electrical connection 100 between the tongue of the switch relay and the tongue of the main line relay, a condenser interposed in said connection, a corrector relay having its coils connected in series, the terminal of one coil being connected to the marking stop of the switch relay, the other terminal of said coil being connected to the RCC stop of the tuning fork and the terminal of the other coil of the corrector relay being connected to the spacing stop of the switch relay, a holding relay, a corrector magnet operating on the tuning fork and controlled by the holding relay, means whereby the tongue of the corrector relay when in position against one of its stops will energize the holding relay and the corrector magnet and when in position against its other stop will short circuit the holding relay and de-energize the corrector magnet, and a driving 110 magnet operating upon the tuning fork and electrically connected to the DC contact of the tuning fork.

12. A regenerative vibratory repeater 125 apparatus for telegraph system wherein the signals transmitted are of unit length or multiple unit length, comprising a main line relay, a vibrating tuning fork having two arms one arm carrying a tongue LT and the other arm carrying an arm RT, a pair of 130

contacts LCC and RCC for said tongue LT, a pair of contacts DC and SC for the said tongue RT, a transmitting relay having one of its coils electrically connected to the SC contact of the tuning fork, the other coil of said transmitting relay being connected to the relay tongue and to ground through a leak resistance, a locking relay having one of its coils connected to the relay tongue and to that coil of the transmitting relay which is electrically connected to the SC contact of the tuning fork, the other coil of the said locking relay being connected to ground and to the tongue of the main line relay, a switch relay having its coils connected in series with one terminal connected to the tongue of the main line relay and the other terminal connected to the LCC contact of the tuning fork, an electrical connection between the tongue of the switch relay and the tongue of the main line relay, a condenser interposed in said connection, a corrector relay having its coils connected in series, the terminal of one coil being connected to the marking stop of the switch relay, the other terminal of said coil being connected to the RCC stop of the tuning fork and the terminal of the other coil of the corrector relay being connected to the spacing stop of the switch relay, and means controlled by the corrector relay to vary the speed of vibration of the tuning fork.

13. A regenerative vibratory repeater apparatus for telegraph systems wherein the signals transmitted are of unit length or multiple unit length, comprising a main line relay, a vibrating tuning fork having two arms one arm carrying a tongue LT and the other arm carrying an arm RT, a pair of contacts LCC and RCC for said tongue LT, a pair of contacts DC and SC for the said tongue RT, a transmitting relay having one of its coils electrically connected to the SC contact of the tuning fork, the other coil of said transmitting relay being connected to the relay tongue and to ground through a leak resistance, a locking relay having one of its coils connected to the relay tongue and to that coil of the transmitting relay which is electrically connected to the SC contact of the tuning fork, the other coil of the said locking relay being connected to ground and to the tongue of the main line relay, a switch relay having its coils connected in series with one terminal connected to the tongue of the main line relay and the other terminal connected to the LCC contact of the tuning fork, an electrical connection between the tongue of the switch relay and the tongue of the main line relay, a condenser interposed in said connection, a corrector relay having its coils connected in series, the terminal of one coil being connected to the marking stop of the switch relay, the tongue of the main line relay, a condenser interposed in said connection, a corrector relay having its coils connected in series, the terminal of one coil being connected to the marking stop of the switch relay, the other terminal of said coil being connected to the RCC stop of the tuning fork and the terminal of the other coil of the corrector relay being connected to the spacing stop of the switch relay, and means controlled by the corrector relay to vary the speed of vibration of the tuning fork.

14. A regenerative vibratory repeater apparatus for telegraph systems wherein the signals transmitted are of unit length or multiple unit length, comprising a main line relay, a vibrating element, a transmitting relay, means whereby the vibrating element will permit the transmitting relay to operate only at signal unit intervals, means connecting the transmitting relay to the main line relay whereby the character of the signals sent out by the transmitting relay will be governed by the signal impulses received by the main line relay, a switch relay operated by the main line relay, a corrector relay controlled by the switch relay, means for normally maintaining the tuning fork vibrating at a speed slightly slower than the speed of the received signal units, means controlled by the corrector relay for causing the tuning fork to vibrate at a speed faster than the speed of the received unit signals, and means whereby the operation of the corrector relay will be controlled by the vibrating element.

15. A regenerative vibratory repeater apparatus for telegraph systems wherein the signals transmitted are of unit length or multiple unit length, comprising a main line relay, a vibrating tuning fork, a contact for the said fork, a transmitting relay having one of its coils electrically connected to the contact of the fork, the other coil of said transmitting relay being connected to the relay tongue and to ground, and a locking relay having one of its coils connected to the relay tongue and to that coil of the transmitting relay which is electrically connected to the contact of the tuning fork, the other coil of the said locking relay being connected to ground and to the tongue of the main line relay.

16. A regenerative vibratory repeater apparatus for telegraph systems wherein the signals transmitted are of unit length or multiple unit length, comprising a main line relay, a vibrating tuning fork, a contact for the said fork, a transmitting relay having one of its coils electrically connected to the contact of the fork, the other coil of said transmitting relay being connected to the relay tongue and to ground, a locking relay having one of its coils connected to the relay tongue and to that coil of the transmitting relay which is electrically connected to the tongue of the main line relay.

contact of the tuning fork, the other coil of the said locking relay being connected to ground and to the tongue of the main line relay, and means operated by the received signals and the tuning fork to maintain the tuning fork in synchronism with the units of the received signals.

17. A regenerative vibratory repeater apparatus for telegraph systems wherein the signals transmitted are of unit length or multiple unit length, comprising a main line relay, a vibrating tuning fork, a contact for the said fork, a transmitting relay formed with differential windings and having one of its coils electrically connected to the contact of the fork, and a locking relay having differential windings and having one of its coils connected to the relay tongue and to that coil of the transmitting relay which is electrically connected to the contact of the tuning fork, the other coil of the said locking relay being connected to ground and to the tongue of the main line relay.

18. A regenerative vibratory repeater apparatus for telegraph systems wherein the signals transmitted are of unit length or multiple unit length, comprising a main line relay, a vibrating tuning fork, a contact for the said fork, a transmitting relay formed with differential windings and having one of its coils electrically connected to the contact of the fork, a locking relay having differential windings and having one of its coils connected to the relay tongue and to that coil of the transmitting relay which is electrically connected to the contact of the tuning fork, the other coil of the said locking relay being connected to ground and to the tongue of the main line relay, and means operated by the received signals and the tuning fork to maintain the tuning fork in synchronism with the units of the received signals.

19. A regenerative vibratory repeater apparatus for telegraph systems wherein the signals transmitted are of unit length or multiple unit length, comprising a main line relay, a vibrating tuning fork, a contact for the said fork, a transmitting relay, having one of its coils electrically connected to the contact of the fork, the other coil of said transmitting relay being connected to the relay tongue and to ground, a locking relay having one of its coils connected to the relay tongue and to that coil of the transmitting relay which is electrically connected to the contact of the tuning fork, and means operated by the received signals and the tuning fork to increase the speed of the tuning fork whenever the speed of vibrations thereof falls below the normal speed of the received signal units, thereby to maintain the fork in synchronism with said received signal units.

20. A regenerative vibratory repeater ap-

paratus for telegraph systems wherein the signals transmitted are of unit length or multiple unit length, comprising a main line relay, a vibrating tuning fork, a contact for the said fork, a transmitting relay formed with differential windings and having one of its coils electrically connected to the contact of the fork, a locking relay having differential windings and having one of its coils connected to the relay tongue and to that coil of the transmitting relay which is electrically connected to the contact of the tuning fork, the other coil of the said locking relay being connected to ground and to the tongue of the main line relay, a corrector relay operated by the tuning fork and signal impulses from the main line relay, and means controlled by the corrector relay to increase or decrease the speed of the tuning fork, thereby to maintain said fork in synchronism with the units of the signals received by the main line relay.

21. In a regenerative vibratory repeater, a main line relay, a locking relay, a transmitting relay, a vibrating element, a contact for said vibrating element, means whereby the locking relay will be normally controlled by the main line relay, and means whereby when the vibrating element touches its contact the locking relay will be prevented from operating and the transmitting relay will be connected to said locking relay.

22. In a regenerative vibratory repeater, means for generating current reversals of unit length independently of the received signals said means comprising a locking relay, a transmitting relay, a positive and negative source of direct current for the transmitting relay, a vibrating element, a contact for said vibrating element, means whereby the locking relay may be placed in circuit with the transmitting relay through a leak resistance, and means whereby when said vibrating element touches its contact the locking relay will be prevented from operating and the transmitting relay will be connected to said locking relay.

23. In a regenerative vibratory repeater, means for generating current reversals of unit length independently of the received signals said means comprising a locking relay, a transmitting relay, a positive and negative source of direct current for the transmitting relay, a vibrating element, a contact for said vibrating element, and means whereby when said vibrating element touches its contact the locking relay will be prevented from operating and the transmitting relay will be connected to said locking relay.

24. In a regenerative vibratory repeater, means for generating current reversals of unit length independently of the received signals said means comprising a locking relay, a transmitting relay, a positive and

- negative source of direct current for the transmitting relay, a vibrating element, a contact for said vibrating element, and means whereby when said vibrating element touches its contact a current impulse of unit length will be sent out by the transmitting relay, the locking relay and the transmitting relay being so connected in circuit that each impulse sent out by the transmitting relay will be of the same unit length as the preceding impulse but of opposite polarity.
25. In a regenerative vibratory repeater, means for generating current reversals of unit length independently of the received signals said means comprising a main line relay, a locking relay, a transmitting relay, a positive and negative source of current for the transmitting relay, means whereby the locking relay will be normally controlled by the main line relay, a vibrating element, a contact for said vibrating element, means whereby the main line relay may be cut out of circuit with the locking relay and the locking relay placed in circuit with the transmitting relay through a leak resistance, and means operating with the main line relay cut out whereby when said vibrating element touches its contact the locking relay will be prevented from operating and the transmitting relay will be connected to said locking relay.
26. In a regenerative vibratory repeater, means for generating current reversals of unit length independently of the received signals said means comprising a main line relay, a locking relay, a transmitting relay, a positive and negative source of current for the transmitting relay, means whereby the locking relay will be normally controlled by the main line relay, a vibrating element,
- a contact for said vibrating element, means whereby the main line relay may be cut out of circuit with the locking relay and the locking relay placed in circuit with the transmitting relay through a leak resistance, and means operating with the main line relay cut out whereby when said vibrating element touches its contact a current impulse of unit length will be sent out by the transmitting relay, the locking relay and the transmitting relay being so connected in circuit that each impulse sent out by the transmitting relay will be of the same unit length as the preceding impulse but of opposite polarity.
27. A telegraph apparatus comprising a vibrating element, two relays, a positive and negative source of direct current for one of said relays, and means whereby the oscillation of the vibrating element will cause the two relays to operate to send out on a connected line section current impulses of equal unit length each impulse being opposite in polarity to the immediately preceding impulse.
28. A telegraph apparatus comprising a vibrating element, two relays, a positive and negative source of direct current for one of said relays, a single contact for said vibrating element, said contact being in circuit with a coil of each of said relays, and means whereby the oscillation of the vibrating element will cause the two relays to operate to send out on a connected line section current impulses of equal unit length each impulse being opposite in polarity to the immediately preceding impulse.

In testimony whereof I hereunto affix my signature

ALDER F. CONNERY.
